UNITED STATES PATENT OFFICE

2,221,454

MINING MACHINE

Lewis E. Mitchell, Columbus, Ohio, assignor to
The Jeffrey Manufacturing Company, a corpora-
tion of Ohio

Original application March 21, 1934, Serial No.
716,660. Divided and this application Novem-
ber 21, 1936, Serial No. 112,127

4 Claims. (Cl. 74—124)

My invention relates to low vein, longwall, bottom kerf-cutting machines comprising a pivoted cutter bar adapting it to be used for either shortwall operations, or longwall operations, and one of the objects of my invention is the provision of improved and simplified construction in a device of this type.

A further object of the invention is the provision of a one way jaw clutch with operating means which when operated will retain the clutch in condition to effect a connection whenever the drive shaft is operated in the correct direction but which will permit operation of said drive shaft in the reverse direction without transmission of power.

Further objects of the invention will appear hereinafter, the novel features and combinations being set forth in the appended claims.

In the accompanying drawings,

Fig. 1 represents a plan view of the mining machine embodying my improvement;

Fig. 2 is a side elevational view of the mining machine shown in Fig. 1;

Fig. 3 is an enlarged plan view with certain parts removed and others shown in section, of the haulage or front end of the machine shown at the right hand end of Fig. 1;

Fig. 4 is a sectional elevation taken on the line 4—4 of Fig. 3 looking in the direction of the arrows;

Fig. 5 is an elevational view of the interior structure shown in section at the right hand portion of Fig. 4, the section being taken on the line 5—5 of Fig. 3 looking in the direction of the arrows;

Fig. 6 is a sectional elevation taken on the section line 6—6 of Fig. 3, looking in the direction of the arrows, Fig. 6 being in elevation similar to Fig. 5 but omitting certain parts and adding others; and

Fig. 7 is a sectional plan view taken on the line 7—7 of Fig. 6;

This application is a division of my application for an improvement in Mining machines, Serial No. 716,660, filed March 21, 1934.

By referring to Figs. 1 and 2, it will be seen that the supporting framework of the mining machine comprises an intermediate motor section 43, a front feeding and hauling section 44, and a rear cutting section 45. These sections are detachably connected together by means of stud screws. An elongated kerf cutter 46 projects from the rear end of the cutter-head section 45 and is pivotally connected thereto. Releasable locking mechanism comprising vertical pins 47,

47' is relied on to hold the kerf cutter in the position shown in Fig. 1 during the shortwall operations, or to hold the kerf cutter in laterally projecting positions for longwall operations. The elongated kerf cutter 46 comprises elongated cutter bar 48 with a chain cutter 49 arranged to travel on the periphery thereof.

The feeding and haulage section 44 comprises flexible draft elements which may be ropes as shown at 50 and 51 in Fig. 1, the free ends of which are adapted to be connected to fixed anchorages extraneous to the machine.

As shown in Fig. 1 a cover plate 65 is provided for section 45 and may be secured by means of bolts 69 to the vertical wall plates of the box-like enclosure thereof.

Referring now to the haulage and feeding section 44 of the machine, it will be seen that the forward end of the armature shaft of an electric motor in motor section 43 is coupled to a shaft 141 journaled in ball bearings and secured to the worm 142 which meshes with a worm wheel 143 journaled on the vertical shaft 144. By means of three bolts 145 an eccentric cam 146 is rigidly secured to the hub portion 147 of the worm gear 143. The worm gear 143 and the eccentric cam 146 are respectively mounted on spaced ball bearings 148 and 149 for free rotation relatively to the vertical shaft 144. When the motor operates to rotate the worm 142 rotary motion is imparted through the worm gear 143 to the eccentric cam 146 to freely rotate the latter on the ball bearings 148, 149 relatively to the vertical shaft 144.

When the eccentric cam 146 rotates it engages a circular ring 150 which is mounted by means of the roller bearings 151 for free rotation on the vertical bearing 152, as shown in Figs. 3 and 4.

The ring roller 150 and the vertical bearing 152 are carried on the bell crank lever 153 as shown in Fig. 3. This bell crank lever is pivoted at 154 where it is supported by the frame 155 for oscillation on a fixed vertical axis.

To that end of the bell crank lever 153 remote from its pivot 154, is pivoted at 156 a screw rod 157 which is adjustably connected to the screw-threaded block 158, the latter being pivoted at 159 to the oscillating pawl carrier 160.

By referring to Fig. 4, it will be seen that the pawl carrier 160 is provided with a central circular portion which is journaled on the hub 161 of the ratchet wheel 162, the latter being keyed as indicated at 163 to the upper end portion of the vertical shaft 144. The pawl carrier 160 may be locked in place as shown in Fig. 4 by means of the

cylindrical bracket 164 suspended from the bottom of the plate 165 which is secured by bolts 167 to the box-like structure comprising the vertical plates 168.

5 The cover plate 166 may be fastened to the plate 165 by the machine screws 166', there being apertures in the plate 166 that may fit over the heads of bolts 167 as shown in Fig. 1.

A central circular cover plate 169 may be connected by means of the screws 170 as shown in Fig. 1, to the central portion of the plate 165. When the plate 169 is removed access may be had to the chamber 171 to lubricate the ball bearings 172 which fit in the cylindrical recess in the bracket 164. The ball bearings 172 afford a means of journaling the upper end of the vertical shaft 144 in the bracket 164.

When the cover plate 165 is removed access may be had to the chamber 173 and the mechanism therein. It should be understood that the chamber 173, when all the parts are assembled and when the covers are attached, affords a closed lubricating chamber for the worm gearing and the ratchet feeding mechanism, all of the parts shown in Fig. 4 in the chamber 173 running in oil.

Pivoted at 174 to the pawl carrier 160 is a spring pressed pawl 175 in position to engage the teeth of the ratchet wheel 162. It will thus be seen that when the cam 146 is rotated, the bell crank lever 153 will be oscillated and the pawl and ratchet mechanism will be intermittently actuated to effect a step by step feeding movement of the vertical shaft 144 in an anti-clockwise direction as viewed in Fig. 3. A spring pressed retaining pawl 176 is pivotally mounted on the axis 154 for movement independently of the bell crank lever 153 and in position to engage the ratchet teeth to prevent reverse movement of the vertical shaft 144. By means of the adjustment which may be effected between the members 157 and 158 the pawl 175 may be adjusted so as to properly enter the notch between the ratchet teeth when the roller 150 is nearest the vertical shaft 144.

45 The rotation of the cam 146 thrusts the roller 150 outwardly away from the shaft 144 and thereby causes a forward anti-clockwise movement of the pawl 175 together with the ratchet wheel 162. In order to return the pawl 175 to its initial position a restoring spring shown at 177 in Fig. 3 is relied upon. This spring is located in the tube between the transverse partition 179 and the head 180 which is pivotally connected at 181 to the link 182 the other end of which is pivoted at 55 183 to the bell crank lever 153.

The restoring movement or return throw of the pawl 175 may be varied or regulated in accordance with the extent of feed desired by mechanism including hand wheel 190 for adjusting the tube having partition 179 in the tubular casing 186.

Adjustments may also be made to cause the pawl 175 to move the ratchet wheel either one notch, two notches, three notches, or four notches, as may be desired. Full speed feeding transmission mechanism may thus be effected for purposes hereinabove more fully explained. It should be particularly noted, however, that all feeding movements or step by step advances of 70 the ratchet wheel 162 are unidirectional irrespective of the direction of rotation of the armature shaft. That is to say, it is immaterial whether the motor is rotating in one direction or in a reverse direction. The rotation of the cam 146 will always cause oscillation of the bell crank 153

so that the reciprocation of the pawl 175 will always be the same and the rotation of the shaft 144 as viewed in Fig. 3 will always be in an anti-clockwise direction.

At the lower end of the vertical shaft 144 as shown in Fig. 4 is a pinion 197 which meshes with a gear 198 journaled by means of the ball bearings 199 to the vertical bearing 200 extending upwardly from the bottom plate 201 of the supporting frame of the haulage and feeding section 44. The gear 198 meshes with the relatively larger gear 202 which is keyed at 203 to the cylindrical hub 204 to the upper end of which is connected one element 205 of a friction clutch 206, the other element 207 of which is located on the 15 interior of the rope drum 208. The bushing 209 is pressed into the sleeve 204 for journaling on the vertical stationary bearing 210, the latter being secured to the top plate 234 by being keyed thereto as shown in Fig. 4.

20 The gear 202 meshes with a similar gear mounted to rotate about vertical bearing 212 which is similar to the vertical bearing 210. Also mounted to rotate about the vertical axis of the bearing 212 is a rope drum 213, and between the 25 similar gear and the rope drum 213 is a sleeve friction clutch and rope drum similar in all respects to the structure shown at the left hand portion of Fig. 4. The gear 202 rotates in an anti-clockwise direction as viewed in plan and the similar gear rotates in a clockwise direction and the ratio between these gears is such that the gear 211 will rotate approximately ten percent faster than the similar gear.

30 As shown in Fig. 4 the hub 216 is provided with a cup-shaped bearing 214 which is held against rotation relative to the bottom plate 201 by means of the pin 215. The hub 216 of the large spur gear 202 rests on the bearing plate 214 within the cylindrical flange 217 which affords an oil cup. 40 This hub 216 carries the portion 204 of the clutch element 205. The upper end of the hub 216 is provided with a ring packing 218 which bears against the inner surface of the stationary ring 219 to form a dirt seal, the ring 219 being mounted in a circular opening in the cover plate 220. This cover plate may be provided with an extension for the space in which the similar gear rotates. A vertical extension may also be provided at 222 (Fig. 4).

45 By providing a floor 221 for the chamber 173 as shown in Fig. 4, a separate closed chamber 223 may be provided for the spur gearing. The central portion of the floor plate 221 may also afford support for the outer race of the ball bearing 230. Suitable lubricating means may be provided for the spur gearing in the closed chamber 223.

50 Connected to and wound on the rope drum 208 is a rope 50 the free end of which is adapted to be connected to a fixed anchorage in the mine extraneous to the machine. Connected to and wound on the rope drum 213 is a rope 51 the free end of which is also adapted to be connected to a fixed anchorage in the mine. The application of power transmitted from the motor to each rope drum is controlled by the friction clutch associated therewith. As above stated, each of the rope drums 208 and 213 is provided with its own friction clutch and each friction clutch is 70 operated by the mechanism shown in Fig. 4.

55 A transverse top plate 234 is securely bolted to the side walls of the frame of the section 44 and the upper ends of the vertical cylindrical bearings 210 and 212 are secured thereto as to 75

prevent rotation of said vertical bearings relative to the supporting frame of the machine. Beneath the plate 234 and keyed to the stationary bearing 210 at 235 is a screw-threaded bushing 236 which is provided in its lower inner side with a seat 237 for a ball bearing 238. It will thus be seen that the sleeve 204 is mounted so that it will have no vertical movement relative to the bearing 210 but may rotate with the bushing 209 while provided with the thrust bearing 238 at its upper end.

Journalled on the bushing 239 surrounding the sleeve 204 is a sleeve-shaped hub 240 at the interior of the rope drum 208. The rope drum is therefore mounted for rotation on the sleeve 204 and the latter in turn is mounted for rotation about the vertical axis of the bearing 210.

Mounted at the upper side of the drum 208 as shown at 241 is the outer race 242 of a ball bearing 243 the inner race 244 of which is riveted as shown at 245 to the wheel 246 screw-threaded on to the screw-threaded bushing 236.

Radial spokes or handles 247 on the wheel 246, some of which handles always project out from beyond the plate 234, may be used to turn the wheel 246 on the screw 236 to lift or lower the ball bearing 243. This ball bearing supports the rope drum and also the clutch member 207. Therefore, when the ball bearing 243 is lifted the clutch is applied to direct transmission of power from the spur gear 202 to the flexible draft element or rope 50. In a similar manner transmission of power from the similar spur gear to the rope drum 213 connected thereto may be effected by grasping the radial handles 247 and turning the wheel 246 to obtain a pull on the rope 51. As shown in Fig. 3, when the two rope drums are rotated in opposite directions and each unidirectionally, pulls will be exerted on both of the ropes 50 and 51.

As shown in Figs. 1, 2 and 3 rope directional sheaves may be located at various corners of the machine. The directional sheaves may be superimposed as shown at the right hand end of Fig. 2, the wider sheave 232 being used for a rope extending directly from the rope drum, and the upper sheave 233 being used when the rope 50 is directed around the same. One directional sheave 248 is sufficient for the rope drum connected to the larger spur gear 202.

At the rear end of the machine a directional sheave 249 may be mounted on an arm 250 which is detachably connected at 250 to a depending bracket at either corner on opposite sides of the machine. During longwall operations the brackets remain within the confines of the supporting framework.

In order to slide the machine over the mine bottom at a relatively fast or haulage speed, mechanism is provided as shown in Figs. 4 to 7 inclusive, for connecting the worm wheel 143 directly to the shaft 144 and the pinion 197 to drive the latter independently of the pawl and ratchet feeding mechanism shown in Fig. 3. By means of the handle 253 connected to the rock shaft 254 which is journalled on the bearing 255, the slotted disc 56 may be moved clockwise from the position shown in Fig. 6 to a clutch applying position and held there after the handle 253 is released.

In the slot 257 of the disc 256 is pivoted at 258 the upper end of a rod 259 the lower end of which is provided with a nut 260 engaging the lower end of the compression spring 261, the lat-

ter being mounted in a tube 262 the lower end of which is connected to the L-shaped member 263 secured to the arm 264. The other end of the arm 264, as shown in Fig. 7, is secured to a tube 265 journalled on a bearing rod 266 mounted in the brackets 267 and 268. Secured to the other end of the tube 265 is another arm 269. Trunnions 270, 270 carrying a ring 271, are journalled in bearings at the outer ends of the arms 264 and 269 as shown in Fig. 7.

Carried by the ring 271 is a lower clutch element 272 which is provided with beveled clutch teeth 272' adapted to engage the upper clutch element 273 secured to the lower side of the worm gear 143 and having teeth 273' as shown in Figs. 4 15 and 6. The lower clutch element 272 is disc-shaped and its periphery fits in an inner annular groove of the ring 271. The latter may be constructed of semicircular parts bolted together as shown at 274, 274 in Fig. 7 to clamp the ring 20 ring 271 to the clutch elements 272.

It should be particularly noted that the inferior meshing teeth 272' and 273' are provided with such beveled surfaces that when the worm gear 143 is rotated in a clockwise direction as viewed in plan, the clutch 272, 273, will be ineffective to transmit power from the motor to the pinion 197. While it is immaterial whether the motor rotates in one direction or the other when the pawl and ratchet feeding mechanism is to be operated, the worm gear 143 should be rotated only in an anti-clockwise direction when the clutch is applied because such application of the clutch will effect rotation of the ratchet wheel 162 which is keyed to the upper end of the shaft 144 as shown in Fig. 4. The pawl 175 remains in engagement with the ratchet wheel 162 and therefore the shaft 144 must be rotated in an anti-clockwise direction when power is applied directly to the pinion 197. Therefore, when the clutch 272, 273 is applied the motor must be rotated in the proper direction to secure anti-clockwise rotation of the ratchet wheel 162 and the shaft 144.

Any attempt to do otherwise would cause the pawl 175 to lock the shaft 144 against rotation whereupon the clutch teeth 272' and 273' will slip relatively to each other even though the pivot pin 258 is held at dead center or beyond, by the spring 261. In other words, when the clutch is applied by means of the handle 253 it will be spring-loaded and the beveling of the clutch teeth will necessitate rotation of the motor in the proper direction to maintain uni-directional rotation of the driving spur gears for the two rope drums. Consequently, whether the rope drums are rotated by means of the slow speed pawl and ratchet mechanism or by means of the fast speed haulage mechanism the rope drums can be rotated by power only in such directions as to wind up the 60 ropes thereon and can never be operated by power to pay out the ropes. When the ropes are to be payed out the friction clutches may be released to free the drums and the ropes can then be pulled manually for the anchoring of the free ends there- 65 of at predetermined locations in a mine.

As shown in Figs. 2 and 3 all of the feeding and haulage mechanism is located between the top and bottom planes of the machine and between the spaced apart vertical planes which extend through the sides of the cutter frame. The pawl and ratchet feeding mechanism shown in Fig. 3 comprises only a single vertical shaft 144 and the manual mechanism for operating the high speed or haulage clutch shown in Figs. 6 and 75

7, is permanently located inside of the adjacent vertical plane extending through the side of the machine.

As shown in Fig. 4 the worm gear 143 is detachably connected to the cam 146. A plurality of openings spaced circumferentially on the worm gear 143 may be provided so that the cam 146 may have a plurality of positions with respect to the worm gear 143. This arrangement enables the life 10 of the worm gear 143 to be prolonged by adjustment thereof to a new position after wear or a maximum load. The pawl 175 is driving the ratchet wheel 162 in an anti-clockwise direction as viewed in Fig. 3. In other words, the eccentric cam 146 is adjustably secured to the worm wheel 143 so that the relative positions of these parts may be varied to allow a plurality of separate places on the worm wheel in turn to be placed in the position of maximum load and wear, 20 thus securing the greatest possible wear from the worm wheel before replacement is necessary.

It should also be noted that only six gears in all and a ratchet wheel are required to drive the two drums and attain numerous feeding speeds 25 and a relatively fast haulage speed when the clutch of Figs. 6 and 7 is thrown in. In order to enable the use of rope drums each relatively large in diameter while maintaining reduction in the width of the machine, these rope drums are 30 mounted with their vertical axes in a diagonal vertical plane as shown in Fig. 3. That is to say, the space ahead of the motor is utilized for the location of the rope drums and the feeding and hauling mechanism connected thereto, and the 35 rope drums are diagonally arranged within the lateral confines of the machine so that their diameters may be increased. The direction sheaves 233 and 248 also have their vertical axes within the side limits of the machine so that their 40 peripheries will be in positions to direct the ropes approximately in alignment with the sides of the machine when arranged as shown in Fig. 3.

The directional sheaves 248 and 233 shown in Figs. 1 and 2 for receiving the ropes 50, 51 direct 45 from the rope drums are preferably tapered upwardly or provided with a conical surface to facilitate the winding of the ropes on the drums and the unwinding of the same therefrom during the various operations above described. Such 50 tapering tends to keep the ropes up notwithstanding floor anchorages, thereby assuring proper winding of the ropes onto the rope drums.

The term "Shortwall" used herein is the trademark of The Jeffrey Manufacturing Company, a 55 corporation of Ohio, the assignee of this application, said trade-mark having been registered October 31, 1911, in Class 23, Cutlery, machinery, and tools, and parts thereof, registration No. 84,006, and renewed June 9, 1931.

60 Obviously those skilled in the art may make various changes in the details and arrangement of parts without departing from the spirit and scope of the invention as defined by the claims

hereto appended and we therefore wish not to be restricted to the precise construction herein disclosed.

Having thus described and shown an embodiment of my invention, what I desire to secure by Letters Patent of the United States is:

1. In apparatus of the class described, a gear train including a shaft and means for driving it comprising a clutch having a direct drive element, of a driven element, another drive element 10 for driving said shaft including means preventing rotation of said driven element in one direction, said direct drive and driven elements having co-operating sets of teeth at least one set of which is beveled, and operating means for said clutch 15 including means to shift said direct drive and driven elements into engaging relation, said operating means including a spring which allows said direct drive element to rotate while said driven element remains stationary when said operating means is in clutch engaging position, should said direct drive element be driven in the wrong direction.

2. In apparatus of the class described, the combination with a shaft, of a gear train for driving said shaft including a slow speed pawl and ratchet drive, a retaining pawl preventing reverse rotation of said shaft, a high speed drive including a jaw clutch having cooperating teeth one group of which is beveled, and operating means for said 30 jaw clutch so constructed and arranged that when said gear train is driven to rotate said shaft against the action of said retaining pawl the clutch elements will slip relative to each other.

3. In apparatus of the class described, the combination with a shaft to be driven, of means for driving said shaft in one direction and preventing movement thereof in the opposite direction, a clutch for driving said shaft independently of said driving means, said clutch comprising 40 toothed drive and driven elements at least one of which has beveled teeth whereby when said drive element rotates in the proper direction said shaft will be driven and when it rotates in the opposite direction said clutch will become disengaged, and 45 means for releasably holding said teeth in engagement.

4. In apparatus of the class described, the combination with an element to be driven, of means for driving said element in one direction at one speed including pawl and ratchet mechanism having a retaining pawl to prevent reverse rotation of said element, a clutch for driving said element independently of said pawl and ratchet mechanism, said clutch comprising drive and driven elements so constructed and arranged as to drive said element to be driven positively in one direction and to slip when said drive element is rotated in a reverse direction, and means for releasably holding said drive and driven elements in operative relation regardless of the direction said drive element is driven.

LEWIS E. MITCHELL.
